UNITED STATES PATENT OFFICE.

JOHN J. MEEHAN, OF DENVER, COLORADO, ASSIGNOR TO THE NATIONAL SALES COMPANY, OF DENVER, COLORADO, A CORPORATION OF COLORADO.

RAZOR-STROPPER.

996,107.

Specification of Letters Patent. Patented June 27, 1911.

Application filed April 12, 1910. Serial No. 555,108.

To all whom it may concern:

Be it known that I, JOHN J. MEEHAN, citizen of the United States, residing in the city and county of Denver and State of Colorado, have invented certain new and useful Improvements in Razor-Stroppers; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to improvements in razor stroppers, being more especially intended for use in sharpening double-edged blades, though it may be employed with other blades, if desired.

20 My present invention may be considered an improvement over the construction set forth in United States Letters Patent No. 942,731, dated December 7th, 1909.

My present invention relates more particularly to the means for rocking the blade-carrying device as the strop is pulled back and forth over a rocking member, or in engagement therewith. This rocking member is rigidly connected with an arm which is 25 pivotally connected with another arm which is in turn rigidly connected with a blade-carrying spindle. The strop preferably engages a pair of pins or rods which are connected with the rocking member on opposite 30 sides of a plane passing centrally through the device parallel with the sides of the frame. As the strop is pulled in one direction, it exerts a leverage on the side of the rocking member where the pull is exerted, 35 thus making the rocking action very sensitive, the said action being communicated to the blade-carrying spindle.

Having briefly outlined my improved construction, I will proceed to describe the 40 same in detail, reference being made to the accompanying drawing in which is illustrated an embodiment thereof.

In this drawing: Figure 1 is a front view of my improved device. Fig. 2 is a section taken through the center of the device parallel with the sides of the frame or casing.

Fig. 3 is a side elevation of the same looking in the direction of arrow 3, Fig. 1. Fig. 4 is a view looking in the direction of arrow 4, Fig. 1, the strop members being broken away below the frame. Fig. 5 is a section taken on the line 5—5, Fig. 1. Fig. 6 is a similar section, showing the rocking member turned to its limit of movement in one direction whereby the edges of the double-edged blade are caused to engage the runs of the strop on opposite sides. Fig. 7 is a similar view showing a slightly modified form of construction, or rather a modified form of use, since in this case the strop engages the rocking device at the top while in the other forms of construction the strop engages the pins below the top or housing of the rocking device. Fig. 8 is a side view of the blade-carrying spindle or the device into 60 which the blade-holder is inserted, preparatory to beginning the sharpening operation. This is a view looking in the direction of arrow 8, Fig. 9. Fig. 9 is an edge view of the same, or a view looking in the direction 65 of arrow 9, Fig. 8. Fig. 10 is a top plan view of the blade-holder. Fig. 11 is an edge view of the same. Fig. 12 is a plan view of a double-edged blade of the Gillette type. Fig. 13 is a plan view showing the blade applied to the blade holder.

The same reference characters indicate the same parts in all the views.

Let the numeral 5 designate a casing closed on opposite sides, as shown at 6. This 85 casing is cut away at the sides above the members 6. The latter are, however, connected at their ends as shown at 7. These ends of the casing have upward extensions 8 in which is trunnioned a rocking frame 9 90 having depending members 10 provided with trunnions 12 which are journaled in the end extensions 8 of the casing. In the depending members 10 of the rocking frame, are mounted two bearing pins 13 located on 95 opposite sides of the trunnions. These bearing pins may consist of small spindles 14 and sleeves or rollers 15 mounted to turn freely thereon. The spindles 14 may be either journaled or fast in the end members 100 10 of the rocking frame. If the parts 15 are mounted to turn freely, it reduces the

friction between the strop 16 and the bearing parts. It is not necessary that there should be any special friction between the strop and the said bearing pins since the 5 pressure of the strop upon the pins, will necessarily impart the rocking movement to the member 9, by virtue of the fact that the pins are located on opposite sides of a plane passed through the trunnions of the rock- 10 ing member and parallel with the sides 6 of the casing.

As shown in the drawing, the rocking member 9 is provided with a transversely curved cap 17, which connects the end members 10, as heretofore explained. The casing extensions 8 project above the trunnions 12 of the rocking member and a spacing-bar 18 has its ends pivoted as shown at 19 in the upper extremities of the extensions 8.

20 Short chains or flexible devices 20 are connected with apertured lugs 21 with which the spacing-bar 18 is provided. The opposite extremities of these chains are connected with a ring 2 which may be connected with 25 a nail, a stationary hook, or any suitable stationary device affording the necessary resistance during the stropping operation. At one extremity of the rocking member 9, the trunnion 12 is provided with an extension 30 12^a with which is rigidly connected one extremity of an arm 22 which projects downwardly parallel with the end of the casing, its lower extremity being pivotally connected as shown at 23 with a short arm 24, 35 the latter being secured by means of a screw 25 to one extremity 26 of a rock-spindle 27. The hub 28 of this spindle is slotted as shown at 29 to receive the short arm 24, which together with its companion arm 22 40 forms a sort of toggle, whereby the rocking movement is transmitted from the member 9 to the member 27. By virtue of the recess or slot 29, it becomes practicable to secure the short arm 24 in proper operative relation 45 with the hollow spindle. This spindle is slotted as shown at 30, the slot being open at one end as shown at 31, to receive a blade-holder 32 which is adapted to be inserted endwise into the hollow spindle. This 50 blade-holder 32 is provided with short lugs 33 adapted to enter openings 34 formed in a blade 35 which as shown in the drawing is of the Gillette type, having edges 36.

Preparatory to using the device, the 55 blade-holder 32 is withdrawn from the rock-spindle 27, the parts being originally in the position shown in Fig. 1. The blade is then applied to the holder as shown in Fig. 13, after which the blade and holder are in- 60 serted endwise through slot 38, formed in one end of the casing. The device is then ready for use, it being assumed that the strop 16 has been threaded through the rocking member 9 below the cap 17 and en- 65 gaging the pins 13. Then as the opposite

extremities of the strop are alternately pulled toward the user, a rocking movement is imparted to the device 9, which movement is transmitted through the toggle members 70 22 and 24, to the rock-spindle 27 to which are imparted partial rotations in reverse directions, whereby the edges of the blade are alternately thrown into engagement with the adjacent surfaces of the strop, whereby both edges of the blade are being simultaneously engaged by the strop, but on opposite sides. It will be understood that the rocking movement of the spindle 27, always has a direction the reverse of that of the member 9 but the rocking action is simultaneously 80 imparted to both members, to the member 9 directly by the action of the strop, and to the member 27, through the medium of the toggle.

In the form of construction shown in Fig. 85 7, the strop is passed over the cap 17 of the rocking member 9, care being taken to leave room enough for this purpose, below the spacing bar 18. The opposite extremities of the strop 16 are preferably provided with 90 metal loops 37 which are connected with the strop members proper by means of clasps 39, each consisting of a plate 40 connected with the loop as shown at 41. Each plate has a clasp 42 pivoted in the ends 43 of the plate 95 as shown at 44. When it is desired to detach the loops 37, it is only necessary to raise the clasp 42. When it is desired to secure the clasps to the extremities of the strop, the latter is passed between the members of 100 the clasp after which the latter is pressed inwardly in the same manner as a suspender clasp.

Having thus described my invention, what I claim is:

1. A razor stroppe, comprising a casing having parallel side members connected at their ends, one end of the casing having a slot, the casing ends having extensions, a 110 rocking member trunnioned in said extensions and having pins on opposite sides of the center, the said member having a transversely curved cap above the pin, a flexible strop engaging said pins, a rock-spindle connected in operative relation with the rocking member, a blade-holder inserted endwise in the said spindle, the latter being slotted to allow the edges of a double-edged blade to protrude, the end extensions of the casing being carried upwardly above the rocking member, and a spacing bar connected with the end casing-extensions above the rocking member, for the purpose set forth.

2. A razor stroppe comprising a casing, having parallel side members connected at their ends, the ends of the casing having upward extensions, a member having its extremities trunnioned in the said end extensions of the casing, and carrying bearing pins located on opposite sides of a plane 125 130

passed centrally through the casing parallel with the sides of the latter, the said member having a transversely curved cap above its bearing pins, and located below the top 5 of the upward extensions of the ends of the casing, a blade-carrying rock spindle journaled in the casing, and an operative connection between the said member and the

rock spindle, and a strop engaging the rock-
ing member for the purpose set forth. 10

In testimony whereof I affix my signature in presence of two witnesses.

JOHN J. MEEHAN.
